UNITED STATES PATENT OFFICE.

RICHARD MONTGOMERY RODDEN, OF MONTREAL, QUEBEC, CANADA.

COLLAR.

1,116,488.

Specification of Letters Patent. Patented Nov. 10, 1914.

Application filed November 25, 1911. Serial No. 602,460.

To all whom it may concern:

Be it known that I, RICHARD MONTGOMERY RODDEN, of the city of Montreal, in the Province of Quebec and Dominion of Canada, have invented new and useful Improvements in Collars, and do hereby declare that the following is a full, clear, and exact description of same.

This invention relates to improvements in 10 collars, and the main object is to provide a collar which will have the appearance of an ordinary standing collar combined with the convenience of the folded collar.

A further object is to provide a collar 15 adaptable to men's or women's wear which may be finished as a standing or wing collar or as an ornamental collar for men or women, by folding as desired.

The ordinary standing collar, such as is 20 used for evening wear or the same collar with the corners folded down, known as the wing collar, is preferred by many persons but have been more or less supplanted by the fold collar largely on account of the 25 great ease with which the tie is held in place by these latter collars. The fold collar is also preferred on account of its superior fit, it being held against gaping at the top by the specially formed tongue of one end enga- 30 gaging the fold of the other end.

The present invention aims to combine the two forms and produce a resulting collar having the most desirable features of each form. This end is attained by forming 35 a collar of substantially the same shape as the standing collar, and providing the lower portion thereof with an internal flap having at the ends tongues of the same form as are used in the fold collars. The button 40 holes are formed in this flap and when in use the tie is held between the collar and flap in the same manner as in a fold collar.

In the drawings which illustrate this invention:—Figure 1 is a perspective view of 45 the collar. Fig. 2 is a similar view showing the corners folded out to produce a wing collar. Fig. 3 is a perspective view of the collar as finished for either women's or men's wear. Fig. 4 is a plan view of the 50 outer face of the collar. Fig. 5 is a plan view of the inner face of the collar. Fig. 6 is a cross sectional view of the collar. Fig. 7 is a cross sectional view of the collar, folded as shown in Fig. 3.

55 Referring more particularly to the drawings, 11 designates the collar body proper,

having an internal flap 12 connected thereto at a suitable line intermediate the upper and lower edges 13 and 14 respectively of the body. This flap 12 is provided at the ends 60 with tongues 15 and 16, the latter of which, 16, has a suitably curved upper edge 17 adapted to lie in the top of the space between the opposite ends of the collar body and flap in the well known manner to hold 65 the collar from gaping. The upper edge 13 of the collar is substantially straight, while the lower edge is suitably curved to fit the wearer's neck and may be provided at the back with a notch 18 positioned to disclose the back button hole 19 formed in the flap and also to adjust the fastening of a bow tie. The front button holes 20 are of the usual type or may, one or both, be of the type shown in Fig. 8.

75 From the foregoing it will be seen that the collar is divided longitudinally into two portions, the upper portion 21 being in the form of a single standing collar while the lower portion 22 is in the form of a fold collar. Since, however, the upper and lower 80 portions are continuous on the outer surface of the collar, the appearance will only be that of a single standing collar if the tie 23 is worn with the knot outside the fold, as indicated in Fig. 1. If the tie is worn with the knot inside the fold, as shown in Fig. 2, 85 the appearance will be practically the same as an ordinary fold collar.

In laundering the collar, the corners 24 90 may be turned down to form the well known wings 25 and the tie arranged as pleases the wearer's fancy. Again the upper single portion 21 may be folded down as shown in Fig. 3. This arrangement is purely ornamental and is intended principally for women's use, but it will be understood that men's collars may be laundried in this way if desired, the advantage being that an ordinary height collar and a low warm weather 100 collar are combined in one, and thus do not necessitate the purchase of two sets of collars of different heights. This form of the collar when made especially for women's wear may be slightly higher in the folded 105 portion than the collars made for men's wear, and may be provided near the lower corners 26 with button holes or slots 27 for the reception of a tie, brooch or other ornament. The portion 21 may be suitably ornamented if desired.

110 In order to insure sufficient room between

the body 11 and the flap 12 to prevent any binding of the tie, the flap is provided with a plurality of inverted V-shaped notches 30 extending upwardly from the lower edge of the flap, and terminating at or near the junction of the flap with the body. These notches 30 are preferably arranged in the position shown, but may be located at other points or increased in number if it is found desirable. These notches serve a double purpose. They allow the collar to be ironed flat and when the collar is put on they allow the tension of the tie to contract the lower edge of the flap, so that the flap draws away from the collar body and leaves ample space for the easy adjustment of the tie.

The preferred method of making the collar, having reference particularly to Figs. 6 and 7, is to attach two layers of fabrics, 31 and 32 respectively, together by a substantially straight seam, this seam being at the upper edge of the collar. The layer 31 forms the outer surface of the collar body 11 while the layer 32, which may if desired be a little narrower as shown, forms the inner surface of the collar body and the inner surface of the flap 12. A third layer 33 of the fabric is then connected at its edges to the free edges of the layers 31 and 32. This third layer is folded in between the layers 31 and 32 and is secured to the layer 32 by a line of stitching 34. It will be seen in Fig. 5 that this line of stitching is slightly curved, being nearer the upper edge of the collar at its center than at its ends. In folding the layer 33 the fold is made in a curve slightly greater than the curve of the line of stitching 34, so that when this curve is flattened out and stitched on the line 34 the halves of the layer will tend to separate, as shown in Figs. 6 and 7, thus leaving ample room for the tie when the collar is bent into circular form. This separation of the parts is assisted by the notches 30 when the collar is worn. The spacing of the inner and outer members of a collar, called the "spring", is an essential feature, well known in the manufacture of fold collars. While only the layers of material forming the facing of the collar have been shown it will be understood that the lining or

stiffening material will be treated in the same manner. The dotted line 35 in Fig. 5 indicates the line of fold of the member 33. It may also be found desirable to make the flap 12 separately from the body of the collar and connect the two members at the line 34. It may also be found desirable to make the layer 33 in two parts and connect the same at the fold. In this case, the upper edges of the two parts would preferably have different curvatures in order that when assembled the required spring would be imparted to the collar. The line of fold indicated by the line 34 of stitching is necessarily curved in order that the upper portion 21 of the collar body may be folded down at this line over the lower portion, without causing creasing or buckling of the lower portion or of the flap. In other words, the curved fold line imparts sufficient spring to enable proper folding of the upper portion over the lower.

The right is reserved to make various modifications, which do not depart from the spirit of the invention, and to alter the design of the collar as may be deemed advisable, it being understood that the design shown in the drawings is only for purposes of illustrating the structure and method of manufacture. These collars may be made in soft as well as starched styles.

Having now fully described my invention, I declare that what I claim is:—

In a collar two layers of fabric secured together at their upper edges, a third layer of fabric having its edges secured to the adjacent lower edges of the first two layers, said third layer being folded in a longitudinally extending curve and inserted between the lower portions of the first two layers, and a curved line of stitching attaching the third layer at its fold to one of the first two layers, the curvature of said fold being greater than the curvature of the line of stitching.

In witness whereof I have hereunto set my hand in the presence of two witnesses.

RICHARD MONTGOMERY RODDEN.
